UNITED STATES PATENT OFFICE.

ROBERT GRAHAM PATERSON RITCHIE, OF NIAGARA FALLS, ONTARIO, CANADA.

TOOL FOR AIR BRAKES.

Application filed February 2, 1927. Serial No. 165,448.

The invention relates to improvements in tools for airbrakes as described in the present specification and shown in the accompanying drawings which form part of the same.

Whilst the invention appertains more particularly to airbrakes for railway engines, freight and passenger cars, its use may of course be extended to wherever airbrakes are employed.

It is customary to frequently inspect and clean airbrakes as it is imperative that they be maintained in good working condition and in order to dismantle an airbrake it is usual to remove the non-pressure head so that the piston can be taken out of the cylinder together with its accompanying parts. In removing the non-pressure head, however, it is desirable to first lock it to the piston sleeve so that there will be no pressure upon its bolts at the time they are being unscrewed and also to keep the non-pressure head, piston and sleeve assembled as a unit so as to facilitate cleaning and inspection.

If these parts are not locked together as a unit it will be readily apparent that the piston spring will force the non-pressure head violently off the sleeve endangering the inspector and, furthermore, making it difficult to reassemble the structure.

It is therefore the object of the present invention to provide a simple and useful tool which can be inserted in the hollow piston sleeve and locked to the same by fingers which the device yieldably carries. It also bears an adjustable shoulder for screwing against the non-pressure head to counteract pressure of the piston spring. By thus locking the parts together it is a simple matter to effect their removal and replacement without in any way disturbing their relationship.

The invention consists essentially of a tool for insertion in the piston sleeve having retractile fingers for engaging apertures in the end thereof and bearing a screw threaded ring for adjustably engaging the non-pressure head.

Referring to the drawings, Figure 1 is an elevation partly in section of an airbrake showing the invention applied thereto. Figure 2 is a vertical sectional view through the invention. Figure 3 is a cross sectional view taken on the line 3-3 of Figure 2. Figure 4 is a further sectional view showing a slightly modified form of the present

invention. Figure 5 is a cross sectional view thereof taken on the line 5-5 of Figure 4.

Like numerals of reference indicate corresponding parts in each of the figures throughout the drawings.

In Figure 1, the numeral 10 designates the airbrake cylinder which is connected to the air reservoir 11 at one end and to the non-pressure head 12 at the other end, the connection of the non-pressure head being effected by a series of bolts 13 passing through the abutting flanges 14.

15 is the piston with its accompanying sleeve 16 about which is the helical compression spring 17 which is shouldered against that piston at one end and at the other end against the non-pressure head thus exerting pressure against this latter member tending to force it off the cylinder. The sleeve carries the usual apertures 18 in its rear end.

Having now recounted the airbrake construction the invention itself will be described. 19 is a shell for insertion in the sleeve of the piston and recessed as at 20 to receive the end thereof, thus providing an annulus 21 of greater diameter than the sleeve, which passes thereover. This annulus is screw-threaded to engage a ring 22.

Extended lengthwise of the shell is a pair of fingers 23 which are pivotally secured thereto as at 24 at their rear ends and terminate at their forward ends in finger grips 25. Integral with each finger is a detent 26 which projects through an aperture 27 in the shell so as to pass therethrough and enter an aperture 18 in the sleeve. 27^a is a helical compression spring having its ends shouldered against the pilots carried by the fingers 23 so as to yieldably hold them in a projected position as clearly discernible in Figure 2. In the use of this tool the finger grips 25 are pressed together so as to withdraw the detents 26 sufficiently to permit of the shell being inserted in the sleeve 16, then the fingers are released permitting the detents to enter the apertures 18 thereof. The ring 22 is then screwed so as to press against the non-pressure head to securely lock the same to the piston sleeve. With these units securely locked together it is a simple matter to remove and replace the head for cleaning and inspection.

100 In the modified form shown in Figures 4 and 5, the only difference which exists is

that the fingers 23 carry integral members 28 converting them into bell cranks. These members 28 engage a block 29 by means of pins 30 operating in the slots of the block.

5 Projecting centrally of the shell is a screw 31 which passes through the block and is shouldered against the sides thereof. Its threads 32 engage a bridge 33 carried by the shell while the free end of the screw is 10 squared as at 34 to receive a spanner or other turning key.

To operate the fingers by this modified form of construction it is simply necessary to turn the screw 31 so as to advance it and 15 cause the block 29 to rotate the members 28 sufficiently to retract the detents 26. To engage the detents 26 in the apertures 18 of the sleeve the screw 34 is turned in the opposite direction. It will be observed that the 20 two forms shown of this invention differ in that one provides a positive and the other a negative finger operated mechanism.

What I claim is:—

1. A tool for an airbrake, comprising a 25 shell, fingers carried thereby for entering apertures in the airbrake sleeve and means borne by the shell for engaging the non-pressure head.

2. A tool for an airbrake, comprising a 30 shell, fingers yieldably carried thereby for entering apertures in the airbrake sleeve and means borne by the shell for engaging the non-pressure head.

3. A tool for an airbrake, comprising a 35 shell, fingers carried thereby for entering apertures in the airbrake sleeve and a ring adjustably fitted onto the shell for engaging the non-pressure head.

4. A tool for an airbrake, comprising a 40 shell for insertion in the piston sleeve, retractile fingers carried by the shell for engaging sleeve apertures, and an adjustable member borne by said shell for shouldering against the non-pressure head.

45 5. A tool for an airbrake, comprising a

shell for insertion in the piston sleeve, fingers pivoted to the shell, detents extending from the fingers for engaging sleeve apertures, means for actuating said fingers, and a member borne by said shell for shouldering against the non-pressure head. 50

6. A tool for an airbrake, comprising a shell for insertion in the piston sleeve, fingers pivoted to the shell, projections borne thereby for engaging sleeve apertures, 55 means for actuating said fingers, and a member borne by said shell for shouldering against the non-pressure head.

7. A tool for an airbrake, comprising a shell for insertion in the piston sleeve, fingers pivoted to the shell, detents extending 60 from the fingers for engaging sleeve apertures, and screw mechanism for actuating said fingers.

8. A tool for an airbrake, comprising a 65 shell for insertion in the piston sleeve, fingers pivoted to the shell, detents extending from the fingers for engaging sleeve apertures, a screw threadedly supported by the shell, a block actuated by the screw and a 70 connection extending between the block and the aforesaid fingers.

9. A tool for an airbrake, comprising a shell for insertion in the piston sleeve, fingers pivoted to the shell, detents extending 75 from the fingers for engaging sleeve apertures, a screw threadedly supported by the shell for axial movement, a block shouldered upon the screw, members pinned to the block and rigidly extending from the aforesaid 80 fingers.

10. A tool for an airbrake, comprising a shell, fingers carried thereby for entering apertures in the airbrake sleeve and a ring threadedly engaged with the shell for abutting the non-pressure head. 85

Signed at Niagara Falls, Ontario, Canada, the 26 day of January, 1927.

ROBERT GRAHAM PATERSON RITCHIE.
